UNITED STATES PATENT OFFICE

2,580,517

LIQUID COOLING PUMP AND FAN

Walter B. Clifford, Boston, Mass.; Bess Swenson Clifford, Boston, and Anne C. Post, Wayland, Mass., executrices of said Walter B. Clifford, deceased

Application October 30, 1948, Serial No. 57,597

8 Claims. (Cl. 123—41.46)

1

This invention comprises a new and improved device for controlling the action of fans in fluid cooling systems. Its chief field of use is in connection with internal combustion engines and it will be described as designed for that purpose.

It is well understood that internal combustion engines should be operated for good efficiency at elevated temperatures. Accordingly, it is undesirable to drive the cooling fan when the engine is cold in starting or at any time when the cooling water is substantially below 200° F. or thereabouts. Indeed, ideal operating conditions from the efficiency standpoint would be found if the cooling water could be maintained consistently just below the boiling point. To avoid the danger of overheating, however, most systems are designed for cooling water temperatures not over 160° F.

The object of the present invention is to provide a simple, compact and reliable device for controlling the operation of the fan in accordance with the temperature of the cooling water, that is, to cause rotation of the fan only when and while the temperature of the cooling water exceeds a definite predetermined degree and so to leave the fan idle until the engine has been warmed to the desired point.

With these objects in view, an important feature of the invention consists in a casing or other means providing a fluid passage between the engine jacket and radiator with a power-driven pump or impeller and a rotor concentrically arranged in the passage, one adjacent to the other, for rotation about a common axis, in combination with a fan operatively connected to the rotor and a thermostatic valve for controlling the volume of fluid driven by the pump or impeller through or against the rotor. Thus as the valve is closed, the volume of impelled fluid approaches zero and the rotor and fan remain at rest, while as the valve is opened by fluid of increasing temperature from the engine jacket, the fan is driven at greater and greater speed by the increasing volume of hot fluid so allowed to circulate.

The concentric arrangement of the impeller and rotor is particularly advantageous because of its compactness, its simplicity, and the direct fluid action established between them. These elements may be of the turbo type, the vanes or blades of one directing the fluid so that it acts by impact on the vanes or blades of the other. In this connection, another feature of the invention consists in concentrically arranged vanes for directing the circulating fluid in the proper direction to the blades of the rotating impeller.

2

Other features of the invention consist in novel details of construction whereby a tight liquid seal is provided for the rotary elements of the device, and means whereby efficient direction and control is insured for the fluid in its passage through the impeller and rotor.

These and other features of the invention will be best understood and appreciated from the following description of a preferred embodiment thereof, selected for purposes of illustration and shown in the accompanying drawings, in which:

Fig. 1 is a view of the device in vertical section together with adjacent portions of an automotive engine on which it is installed, and

Fig. 2 is a partial view in cross-section on the line 2—2 of Fig. 1.

In Fig. 1 is shown a portion of the water jacket 10 of an automotive engine. To this is secured a casing 11 in which are formed bearings for the rotating elements of the fan-controlling device and which communicates through a tubular fitting 12 with the radiator. The casing 11 and the fitting 12 are bolted together with an interposed gasket, and a perforated diaphragm 13 is arranged transversely of the passage. The perforations in the diaphragm 13 are opened or closed by a valve 14 thermostatically controlled by a heat sensitive bellows 15 which may be of any well-known commercial construction. As the temperature of the water flowing between the water jacket and the radiator decreases, the valve 14 is operated to close the perforations in the diaphragm 13, and when these perforations are fully closed the circulation of fluid through the passage of the casing 11 is substantially reduced.

The front wall of the water jacket 10 is bored to receive a horizontally projecting tube 16 closed at its outer end by a cap 17. The tube is provided with longitudinal slots 18 and externally of these slots is provided an annular series of vanes 19 which direct fluid passing outwardly through the slots in an approximately tangential direction. These vanes at their inner ends approach closely to the outer wall of the water jacket and are supported by a ring which is secured to the tube 16.

The casing 11 is extended outwardly in the form of a hub 20 in which is provided bearings for a hollow shaft 21 having a splined connection with a driving pulley 23 driven by a V-belt 24. The bearing for this shaft includes a bushing 25 of bronze and graphite which provides at its inner end one element of a circular seal. The other element is supplied by a hub 26 formed

integral or otherwise secured to the hollow shaft 21 and provided with an annular series of blades 27 of the shape shown in Fig. 2. In the assembled device these blades act as a circulating pump in the system forcing the cooling fluid out through the fitting 12 to the radiator and drawing it from the water jacket through the stationary vanes 19.

The shaft 21 is supported at its outer end by ball bearings 28 which are pressed into a recess formed for that purpose in the outer end of the hub 20. A washer 29 is secured in position upon the end of the shaft 21 by a split ring, and a compression spring 30 is interposed between this washer and a washer which covers the ball bearings 28. Accordingly, the hollow shaft 21 is at all times urged outwardly and the outer face of its hub is held in sealing engagement with the bushing 25. It will be understood that the splined connection between the shaft 21 and its driving pulley 23 permits the slight longitudinal movement of the shaft to take place which may be necessary to establish and maintain a sealing relation between the hub 26 and the inner end of the bushing 25.

Within the hollow shaft 21 is provided a solid shaft 31. At its inner end this shaft is journaled in a bronze and graphite bushing 32 which is set into the hub of the hollow shaft. At its inner end the shaft 31 carries a hub 33 and this is provided with a series of blades 34 set at the proper angle to be driven by fluid passing through the stationary vanes 19 as shown in Fig. 2. This may approximate an angle of 45° to the radius of the outer circle of the blades. The shaft 31 passes at its outer end through the hub 35 of the fan, the latter being mounted on ball bearings 36 which are supported in an annular recess provided in the outer end of the hub 20 and held in place by a lock nut 37. The hub 35 is hollow and closed by a cover plate 38 attached thereto by screws. At its outer end the shaft 31 carries a washer and a pair of lock nuts 39. A spring 40 is interposed between this washer and the hub of the fan. The spring tends always to draw the shaft 31 outwardly, thereby establishing and maintaining a sealing relation between the inner end of the bushing 32 and the hub 33 of the rotor.

It is believed that the operation of the device will be understood from the foregoing description, but it may be summarized as follows. The pump or impeller 26-27 is driven at all times by the pulley 23, and at all times tends to draw cooling fluid from the water jacket and expel it through the valve 14 to the radiator. While the engine is cold the valve 14 is shut. Consequently little current flows through the system and the impeller builds up a small hydraulic pressure against the valve 14. As the engine and the cooling fluid warm up, the valve 14 begins to open, permitting the hydraulic current generated by the impeller to flow to the radiator, back to the water jacket and through the short tube 16 to the blades of the rotor 33-34. The fan 41 is, of course, directly driven by the rotor and its speed of rotation and cooling effect, therefore, increases with the temperature of the cooling fluid and the gradual opening of the valve 14. When the valve is fully opened, the rotor will be driven at substantially the speed of the impeller and the speed of the fan 41 will therefore closely approximate that of the belt-driven pulley 23. Preferably and as herein shown, the valve disk 14 is provided with a small

vent hole 4 that permits a continuous slight circulation of cooling fluid to the radiator and throughout the cooling system in order that the temperature of the fluid may be substantially equalized at all times. The minimum predetermined flow thus permitted is negligible so far as its effect in rotating the fan.

It may be noted as a further advantage of my invention that a very considerable improvement in the driving efficiency of the engine is achieved by relieving the engine of the duty of driving the fan throughout the very substantial intervals of time when its cooling action is not required.

Having thus disclosed my invention and described in detail an illustrative embodiment thereof, I claim as new and desire to secure by Letters Patent:

1. An automatic fan-controlling device comprising a casing having a circulating pump and rotor concentrically arranged therein for rotation about a common axis, the rotor having vanes located in the path of fluid circulated by the pump and being driven thereby, power operated means for rotating the pump, a fan operatively connected to the rotor, and a thermostatic valve for controlling the volume of circulating water driven by the pump against the rotor.

2. An automatic fan-controlling device comprising a casing providing a fluid passage between the water jacket and radiator of an engine, a power driven circulating pump with longitudinal vanes disposed within the passage, a rotor with longitudinal vanes concentrically disposed with respect to the pump, a fan operatively connected to said rotor, and a thermostatically operating valve controlling fluid flow through the passage.

3. An automatic fan-controlling device comprising a casing having a fluid passage therein defined in part by a vertical wall, an impeller having longitudinal blades annularly disposed with their ends adjacent to said wall for rotation about a horizontal axis, a rotor concentrically arranged with respect to the impeller, the rotor having vanes located in the path of fluid circulated by the impeller and being driven thereby, a fan connected to the rotor, and a thermostatic valve controlling the volume of fluid through the passage.

4. An automatic fan-controlling device comprising means providing a passage between the water jacket and radiator of an internal combustion engine, an annular series of stationary longitudinally extending vanes in said passage, a power operated impeller having a similar series of vanes concentrically disposed with respect to the stationary vanes, a rotor fluid driven by the impeller, and a fan driven by the rotor about the axis of the impeller.

5. An automatic fan-controlling device comprising a casing providing a passage between the water jacket and radiator of an internal combustion engine and having concentric annular seals in its wall, a power driven impeller and a rotor concentrically arranged within said passage, the rotor having vanes located in the path of fluid circulated by the impeller and being driven thereby, springs holding the impeller and rotor in yielding contact with the said seals and a fan driven by the rotor.

6. An automatic fan-controlling device comprising a casing adapted to be secured to the water jacket of an internal combustion engine and providing a passage between the water jacket

and radiator, said casing having a hub, a hollow shaft journaled in the hub and carrying a turbo-impeller, a solid shaft located within the hollow shaft and carrying a turbo-rotor disposed concentrically within the impeller, means for driving the said hollow shaft, a tube projecting from the water jacket providing a fluid passage concentrically disposed with respect to said shafts, and a thermostatic valve controlling flow through said passage.

7. A fan-controlling device for automotive engines comprising a casing providing a passage between the water jacket of the engine and the radiator, a thermal valve controlling the volume of cooling fluid flow through said passage above a predetermined minimum flow for equalizing the temperature of fluid in the system, a rotor mounted for free rotation in said casing, and a mechanically driven circulating pump concentrically disposed within said passage in operative relation, the rotor having vanes disposed in the path of fluid circulated by the pump and being driven thereby, and a fan connected to said rotor.

8. A fan-controlling device for automotive engines comprising a casing constructed and arranged to be interposed between the radiator and engine block of an internal combustion engine,

5 a power driven pump and rotor mounted adjacent to each other for rotation about a common axis in the casing, the rotor having vanes disposed in the path of fluid circulated by the pump and being driven thereby, the casing providing a fluid passage to and from the pump and rotor, a fan connected to the rotor, and a thermostatic valve in said passage arranged to control the flow of circulating fluid after it leaves the pump and thus to regulate its effect on the rotor.
